[57] CLAIM

The ornamental design for a retractable drawer-type facsimile machine module, as shown and described.

DESCRIPTION

FIG. 1 is a perspective view of a retractable drawer-

type facsimile machine module showing our new design in a drawer-closed position;

FIG. 2 is a top plan view thereof in a drawer-closed position;

FIG. 3 is a right side elevational view thereof in a drawer-closed position, the left side elevational view being a mirror image;

FIG. 4 is a bottom plan view thereof in a drawer-closed position;

FIG. 5 is a front elevational view thereof in a drawer-closed position;

FIG. 6 is a rear elevational view thereof in a drawer-closed position, the rear elevational view in a drawer-open position being identical;

FIG. 7 is a perspective view thereof in a drawer-open position and in a typical operating environment with a laser printer mounted thereon;

FIG. 8 is a perspective view thereof in a drawer-open position;

FIG. 9 is a front elevational view thereof in a drawer-open position;

FIG. 10 is a top plan view thereof in a drawer-open position;

FIG. 11 is a bottom plan view thereof in a drawer-open position; and,

FIG. 12 is a right side elevational view thereof in a drawer-open position, the left side elevational view being a mirror image.

The broken line showing of the laser printer in FIG. 7 is for illustrative purposes only and forms no part of the claimed design.
